CLAIM

The ornamental design for a clamp assembly for a gate operator, as shown and described.

DESCRIPTION

FIG. 1 is a top view of the clamp assembly in an assembled state.

FIG. 2 is a bottom view of the clamp assembly in an assembled state.

FIG. 3 is a left side view of the clamp assembly in an assembled state.

FIG. 4 is a right side view of the clamp assembly in an assembled state.

FIG. 5 is a rear view of the clamp assembly in an assembled state.

FIG. 6 is a front view of the clamp assembly in an assembled state.

FIG. 7 is a right side rear elevation view of the clamp assembly in an assembled state.

FIG. 8 is a right side front elevation view of the clamp assembly in an assembled state.

FIG. 9 is a left side front elevation view of the clamp assembly in an assembled state.

FIG. 10 is a top detail view of the clamp assembly without handle.

FIG. 11 is a bottom detail view of the clamp assembly without handle.

FIG. 12 is a front detail view of the clamp assembly without handle.

FIG. 13 is a rear detail view of the clamp assembly without handle.

FIG. 14 is a left side detail view of the clamp assembly without handle.

FIG. 15 is a right side detail view of the clamp assembly without handle.

FIG. 16 is a right side rear detail elevation view of the clamp assembly without handle; and,

FIG. 17 is a left side front detail elevation view of the clamp assembly without handle.

(Continued)

The broken lines shown in the Figures show portions of the clamp assembly for a gate operator that form no part of the claimed design.
